UNITED STATES PATENT OFFICE.

WILLIAM LOUIS BESSOLO, OF CLEARWATER, CALIFORNIA.

TONGS.

Application filed August 22, 1924. Serial No. 733,475.

This invention relates to tongs and it is an object of the invention to provide a simple, effective, improved tool of this character.

It is an object of this invention to provide tongs which are quick and convenient to operate.

Another object of this invention is to provide tongs which are simple, inexpensive and durable of construction.

10 It is a further object of this invention to provide tongs which are effective and reliable in gripping objects such as casings, pipes, tubings, etc.

15 The various objects and features of this invention will be best and more fully understood from the following detailed description of a typical preferred form of the invention throughout which description reference is had to the accompanying drawings 20 in which

Fig. 1 is a face or plan view of tongs embodying the present invention showing the tool closed or in operating position.

25 Fig. 2 is a view similar to Fig. 1 showing the tool open.

Fig. 3 is a view similar to Fig. 1 showing the tool with one of the cheek plates removed.

30 Fig. 4 is a detailed sectional view taken at the inner end of the handle and

Fig. 5 is a detailed sectional view of the outer part of the links showing the latch provided for connecting the links.

35 The tongs comprise generally a handle or lever 10, two cheek plates 11, connected to the inner end of the handle, a rack member 12, carried by the cheek plates in cooperative relation with the handle, two jaws or link members 13 and 14, connected with the cheek plates and rack member respectively, and a latch 15 for connecting the outer or free ends of the links 13 and 14.

40 The lever 10 may be of the general design and construction common to handles employed in tools of the general character under consideration. In accordance with this invention the inner end of the lever 10 is provided with a series of gear teeth 16. The gear teeth are formed about a center 45 located near the inner end of the lever 10 and are preferably formed directly in or as a part of the lever 10.

50 The cheek plates 11 are arranged at opposite sides of the lever 10 and are pivotally

connected with the lever by a pivot pin 17. 55 The pin 17 connects the cheek plates with the handles at the center or axis about which the teeth 16 are formed. The cheek plates extend a considerable distance beyond the end of the handle, the outer portions A of 60 the cheek plates being adapted to engage the casing or other object handled by the tool. In practice it is preferred to curve the portions A of the cheek plates substantially as I have shown in the drawings. 65

The rack member 12 slidably fits between the cheek plates 11 immediately beyond the end of the lever and is slidably pivotally connected with the cheek plates. In the particular form of construction illustrated 70 in the drawings the rack member is connected with the cheek plates by a pivot pin 19, which is carried between the cheek plates and extends through an opening or slot 20 in the rack member. The pin is 75 tightly carried by the plates and fits freely through the slots. The rack member 12 is provided with a series of teeth 21 adapted to mesh with the teeth 16. The connection between the rack member and cheek plates 80 is such as to hold the rack member in position with its teeth 21 in mesh with the teeth 16 on the handle. In practice the series of teeth 21 is curved substantially as shown in the drawings, and the slot 20 in the rack 85 member is curved to correspond to or is parallel with the series of gear teeth so that the gear teeth 21 and 16 will remain in proper cooperative relation at all times. The relation of the slot and gear teeth is 90 clearly shown in the drawings.

The jaws or links 13 and 14 together with portions A of the cheek plates and the rack member 12 are adapted to encircle or extend around the casing to be handled by 95 the tool. The inner end of the link 13 is pivotally connected with the outer end portions of the cheek plates 11, that is, to the outermost parts of the portion A of the cheek plates so that its inner end is connected to the plates at a point outward of or beyond the pin 19. In the particular construction illustrated in the drawings the link extends between the cheek plates and a pivot pin 25 extends between the cheek 100 plates and through the link to connect what I will term the inner end of the link with the cheek plates. The link 14 is pivotally 105

connected with the outermost part of the rack member 12. I have shown the link 14 yoked to receive the rack member 12 and a pivot pin 26 connecting the yoked part 5 of the link and the rack member.

The outer or free ends of the links 13 and 14 are adapted to be connected together around the object to be handled by the tool. Although the links may be connected in 10 several different ways, I prefer to connect them by a latch 15 carried by one of the links to cooperate with ratchet teeth 30 on the other link. In the drawings I have illustrated the latch 15 mounted on a pivot 15 pin 31, extending between lugs 32 provided on the link 13, and have shown a spring 33 in connection with the latch normally yielding holding or urging it closed. A plurality of ratchet teeth 30 are provided on the 20 outer part of the link 14 to receive the head 34 of the latch 15. By providing a plurality of teeth 30 the links may be connected together in various positions so that the tool will handle casings of various sizes. The 25 outer end portion of the link 13 is yoked so that it slidely receives the outer end portion of the link 14 thus allowing the links to lap together.

In a preferred arrangement I provide 30 lugs or projections 40 on the inner parts of the links 13 and 14 to project into the space occupied by the pipe or casing when the links are in an open position, as illustrated in Fig. 2. The lugs are proportioned and 35 related so that they are engaged by the casing when the tool is applied to the casing and operate to close the links 13 and 14 to the position illustrated in Fig. 1.

In operating the tool it is applied to a 40 casing, or like object, with the links 13 and 14 open as shown in Fig. 1. As the casing comes into position between the portions A of the cheek plates and the rack member 12 it engages the projections 40 on the links 45 causing the links to swing closed to the position shown in Fig. 1. With the links in the position illustrated in Fig. 1 the casing is completely encircled by the tool. As the links 13 and 14 are moved together the latch 50 15 automatically engages the ratchet teeth 30 to connect the links together. With the tool thus applied to the casing the lever 10 is swung or actuated in the direction indicated by the arrow A in Fig. 1, which operation causes pivotal movement between the lever and the cheek plates and movement between the cheek plates and rack member so 55 that the tool is tightened on the casing to firmly grip it. Further movement of the lever 10 will cause the casing to be carried around with the tool. When it is desired to release the tool from the casing the lever 10 is swung back, that is, in the direction opposite to that indicated by the arrow 60 A in Fig. 1 so that the grip on the casing is 65

released and the latch 15 can be freely opened. When the latch 15 is opened the tool can be easily removed from the casing.

The connection between the rack member and cheek plates is an important feature of 70 the tool as it allows the rack member and cheek plates to conform to the casing, prevents the rack member being forced against the casing to injure it, and holds the rack member in position to properly cooperate 75 with the lever.

Having described only a typical preferred form of my invention I do not wish to limit myself to the specific details hereinabove set forth, but wish to reserve to myself any 80 changes or variations that may appear to those skilled in the art or fall within the scope of the following claims:

Having described my invention, I claim:

1. A tool of the character described including, a lever provided at its inner end with teeth, a plate pivotally connected with the lever, a rack member carried by the plate in cooperative engagement with the teeth, and links adapted to engage around a casing, 85 one link being connected with the plate and one being connected with the rack member.

2. A tool of the character described including, a lever having teeth at its inner end, a plate pivotally connected with the lever, a rack member, means connecting the rack member with the plate and guiding it in cooperative engagement with the teeth, and links adapted to engage around a casing, one link being connected with the plate and one being connected with the rack member. 90

3. A tool of the character described including, a lever having teeth at its inner end, a plate pivotally connected with the lever, a rack member, means slidably connecting the rack member with the plate so that it is in cooperative engagement with the teeth, and links adapted to engage around a casing, one link being connected with the plate and one being connected with said member. 105

4. A tool of the character described including, a lever having teeth at its inner end, a plate pivotally connected with the lever, a member having a series of teeth and an opening parallel with the series of teeth, a pin extending from the plate into the opening to hold said member with its teeth in cooperative engagement with the teeth on the lever, and links adapted to engage around a casing, one link being connected with the plate and one being connected with said member. 115

5. A tool of the character described including, a lever having teeth at its inner end, a plate pivotally connected with the lever, a rack member slidably connected with the plate to cooperate with the teeth, a link connected with the plate, a link connected with the rack member, and means for releasably connecting the links together. 125 130

6. A tool of the character described including, a lever having teeth at its inner end, a plate pivotally connected with the lever, a rack member, means slidably pivotally connecting the rack member with the plate at a point beyond the inner end of the lever and so that the rack member is in cooperative engagement with the teeth, a link connected with the plate at a point beyond the connection between the plate and rack member, a link connected with the rack member, and means for releasably connecting the links together.

7. A tool of the character described including, a lever having teeth at its inner end, cheek plates pivotally connected with the inner end portion of the lever, a rack member arranged between the cheek plates, means slidably connecting the rack member and the cheek plates with the rack member in co-operative engagement with the teeth, a link pivotally connected with the cheek plates, a link pivotally connected with the

rack member, and a latch to connect the links.

8. A tool of the character described including, a lever having teeth at its inner end, cheek plates pivotally connected to the inner end portion of the lever, a rack member arranged between the cheek plates beyond the end of the lever and in cooperative engagement with the teeth, a pin extending between the plates and through a slot in the rack member, a link having its inner end pivotally connected between the cheek plates at a point beyond said pin, a link having its inner end pivotally connected with the rack member, a plurality of teeth at the outer end of one of the links, and a latch at the outer end of the other latch adapted to cooperate with the teeth.

In witness that I claim the foregoing I have hereunto subscribed my name this 6th day of Aug. 1924.

WILLIAM LOUIS BESSOLO.
